UNITED STATES PATENT OFFICE.

FRED. H. OTTO, OF GALVA, IOWA.

TRUCK.

SPECIFICATION forming part of Letters Patent No. 378,937, dated March 6, 1888.

Application filed October 10, 1887. Serial No. 251,891. (No model.)

To all whom it may concern:

Be it known that I, FRED. H. OTTO, a citizen of the United States, residing at Galva, in the county of Ida and State of Iowa, have invented 5 certain new and useful Improvements in Trucks for Binder-Platforms; and I do hereby declare the following to be a full, clear, and exact description of the invention, such as will enable others skilled in the art to which it applies 10 to make and use the same.

This invention relates to improvements in trucks for grain-binder platforms; and it consists in the novel construction and combination of parts, all as will be hereinafter fully 15 described, and particularly pointed out in the appended claims.

The annexed drawings, to which reference is made, illustrate my invention, in which—

Figure 1 represents a vertical sectional view 20 of my device. Fig. 2 is a top view, and Fig. 3 is a perspective view, of the angular iron.

Referring by letter to the accompanying drawings, A designates the truck, composed 25 of the side parallel bars, a a, which are connected at the front by a cross-bar, b, and at the rear by a bar, c. In the space between the side bars, a, is located the transporting-wheel d, that is journaled in bearings e on the under side of the side bars, as shown in the drawings.

30 B represents an angular or L-shaped iron having forked end f, which iron fits snugly in a groove, g, made in the front or face of the front cross-bar, whereby a lateral or pivotal movement is prevented and permits only a vertical adjustment of the angular bar. Through 35 the forked end of said bar passes a bolt, i,

which enters the cross-bar b and serves to hold the angular bar in a rigid position when screwed up, and when loosened the bar B can be vertically adjusted to the platform of a 40 binder.

At the rear end of each side bar is a projecting spike, k.

It will be seen that when the truck is applied 45 to a platform under a binder the spikes bite or grip the under side of said binder-platform, while the angular bar, by its horizontal plate l, grips the forward end of said platform, thus being secured thereto, the wheel supporting 50 said platform; and it is simple in construction, durable, and cheap to manufacture.

What I claim is—

1. The truck herein described, consisting of the parallel side bars provided with the spikes and connected front and rear by the end cross-bars, the front bar having the groove and the angular iron having the forked end, the bolt for securing it, and the transporting-wheel journaled thereto, the whole combined and operating as shown, and for the purpose set forth. 55

2. In a truck for binders, in combination therewith an adjustable angle-iron forked at its lower end and bolted thereto, and spikes arranged on the rear portion of the truck, whereby the latter is removably secured to a 60 binder, as and for the purpose set forth.

In testimony whereof I affix my signature in presence of two witnesses.

FRED. H. OTTO.
